E. L. WIEGAND

ELECTRICAL HEATING ELEMENT OF THE STRIP TYPE

Original Filed August 31, 1923

Inventor
Edwin L. Wiegand
By Hull, Brock & West
Atty's.

UNITED STATES PATENT OFFICE.

EDWIN L. WIEGAND, OF DORMONT BOROUGH, PENNSYLVANIA.

ELECTRICAL HEATING ELEMENT OF THE STRIP TYPE.

Original application filed August 31, 1923, Serial No. 660,294. Divided and this application filed March 7, 1924. Serial No. 697,446.

This is a division of my former application, Serial No. 660,294, filed August 31, 1923, and the subject matter of the present case is restricted to a so-called "strip" heater which is one of the several forms of the invention disclosed in said application.

My earlier application relates generally to a novel type of electrical heating device or element consisting generally of a resistor enveloped in a body or compressed mass of refractory material encased in a sheet metal cover or sheath, the primary object of the invention being to provide an electrical heating device or element affording the maximum output of heat at a given temperature, while providing ample safeguard against a possible breaking down of the insulation between the resistor and the sheath or cover. Such a construction permits very intimate contact between the heat radiating surface of the heating device or element and the object to be heated and affords unusual diffusion or spreading out of the enveloped resistor and nearness of the resistor—the source of heat—to said object. Numerous other advantages arising from such a construction are set forth in my former application and it is deemed unnecessary to repeat them here, and in the earlier case their importance is emphasized by a comparison of my improved device or element with prior forms of electrical heating devices of the same general class.

As above stated, the present case has to do particularly with strip heaters which have acquired a distinct place in the art. Such heaters are employed for various purposes. They may be applied to a plate for heating it; or they may be suspended from suitable supports for heating space; or they may be applied to the exterior or interior of a vessel for heating the contents thereof; or they may be disposed inside a hollow heating or drying roll.

In the past, the more common forms of this general type of heater employed the usual resistor wire disposed between sheets of mica, the mica, in turn, being enclosed by and between strips of sheet metal which form a sort of casing that is open at its ends.

An advantage which my improved strip heater possesses over these earlier forms is that it may be readily bent to conform to objects of different shapes to which it may

be applied, as will hereinafter more fully appear, it being readily apparent that where mica sheets are employed for insulation it would be difficult to bend the device or element without greatly impairing if not completely destroying the insulation. Also, in these earlier types of strip heaters, where mica sheets are used as insulation, the expansion and contraction due to the alternate heating and cooling of the device sets up a creeping action between the casing, mica and resistor which results in a breaking up and displacement of the mica sheets or layers and the resistor and an egress of some of the disintegrated mica through the open ends of the casing. Furthermore, the casing, being open at its ends, permitted ingress of moisture and other damaging elements.

Among the several objects of my present invention are to provide an elongated, narrow and comparatively thin electrical heating device comprising a resistor element enveloped within a body of refractory, electrical insulating, heat conducting material that is encased within a sheet metal cover or sheath; to provide, in such a construction, a casing that is completely closed against the ingress of deteriorating agents, as moisture and foreign substances; to provide, in a construction of the foregoing nature, a casing composed of two sheet metal members, one preferably in the form of a channel, and the other a cover between which cover and the web of the channel, the resistor, enveloped in the body of refractory material, is disposed, the edges of the channel being turned over the cover and compressed to hold the parts firmly together; and also to close the ends of the casing by pressing the extremities of the cover and end extensions of the web of the channel together thereby to provide relatively thin tabs which may be used for attaching the device to supports or to objects that are to be heated.

By constructing the sheath or cover as described the element or device is rendered very rigid but by reason of its nature is capable of being readily formed into various shapes, as shall presently be described.

Further and more general objects are to provide an electrical strip heater that is comparatively light, is neat of appearance, is very strong and durable, is practically indestructible from any cause arising within

the scope of its intended use, and is so designed and constructed as to expedite manufacture, and insure production at a low cost.

The foregoing objects, with others herein-after appearing, are attained in the embodiment of the invention illustrated in the accompanying drawing wherein Fig. 1 is a plan view and Fig. 2 is a side elevation of my improved strip heater; Fig. 3 is a longitudinal section through one end of the heater on a somewhat enlarged scale; Figs. 4 and 5 are transverse sections on the same scale as Fig. 3, the heater being shown as flat in the former view and as being transversely curved in the latter view; Figs. 6 and 7 show the strip heater bent to different forms; and Fig. 8 is a fragmentary plan view of a perforated cover that is employed in some instances.

20 Describing the construction by the use of reference numerals, 1 denotes the resistor which preferably, but not necessarily consists of a suitable metallic ribbon or flat wire that is preferably bent into serpentine form. 25 This resistor is completely enveloped by a compact homogeneous mass of granular refractory electrical insulating material 2 which not only supports the ribbon at all points due to its intimate contact therewith but also prevents oxidation of the resistor. 30 Each end of the resistor is connected to a terminal 3 which may be of any suitable type but is preferably similar to that disclosed in my co-pending application Serial 35 No. 555,870, filed April 21, 1922. These terminals are each provided with insulating washers 4 which prevent contact of the terminals with the sheet metal casing composed of a channel receptacle 5 and a cover plate 6 which completely surround the refractory material. The side edges 7 of the receptacle are deflected over the cover plate, as clearly shown in Figs. 1, 4 and 5, and the ends of the casing beyond the terminals 45 3 are flattened, as indicated at 8, and are provided with apertures 9 so that the heater may be conveniently supported on a frame or fastened to an object to be heated. If desired the seams formed by the overlapping side edges 7 and the cover plate 6 may be welded, although for ordinary conditions folding over the edges under high pressure will prove sufficient.

50 In some instances where it is unnecessary to provide a tight seal for the insulating material, I perforate a portion of the metal casing as for example the cover plate 11, as shown in Fig. 8. During the folding and pressing of the side edges of the casing, the refractory material will be forced into the perforations and thereby serve to bond the refractory material and casing together.

60 A strip heating element of this general character is very thin, light in weight, and affords maximum transfer of heat from the

resistor to the object to be heated. The resistor is completely enveloped in a compact mass of refractory material and hence is supported at all points and is completely protected against oxidation. These strip heaters may be longitudinally or laterally bent to various shapes to meet the particular requirements.

In Fig. 5 I have shown the strip heater bent to assume an arcuate cross-section while in Figs. 6 and 7 I have shown the element bent into circular form and U-shape form, respectively. The circular form may be conveniently applied to any cylindrical object as for example a pipe or water tank, while the U-shape form is suitable for application to molds and similar objects. When bent into circular form, as in Fig. 6, a bolt 12 may be engaged through apertures 9 for the purpose of retaining the element in position on the object.

While, so far as the present invention is concerned, I do not limit myself to any particular kind of refractory insulating material, one kind found especially suitable for the purpose is composed of magnesium or aluminum oxide or zirconium silicate, either individually where possible or a compound of them, together when desirable with a binding material such as clay, to give the necessary plasticity during fabrication and to effect homogeneity in the final product. Neither do I limit myself in the broad analysis of the invention to a sheath or cover constructed in the manner illustrated, as obviously the same might take various forms and constructions without departing from the spirit of the invention.

The resistor element may be enveloped in the refractory insulating material in accordance with my Patent No. 1,136,076, issued April 20, 1915, entitled "Process of producing electrical heating devices", or in accordance with my Patent No. 1,398,410, issued November 20, 1921, and entitled "Embedding process."

Having thus described my invention, what I claim is:

1. As a new article of manufacture, an electrical heating element of the strip type, as distinguished from electrical stoves, hot plates and tubular heaters, the same comprising a resistor, an elongated, narrow, relatively thin sheet metal sheath made up of a plurality of parts enveloping said resistor and spaced therefrom, and a mass of granular refractory electrical insulating material of high heat conducting quality filling the space between the resistor and sheath, the resistor being provided with terminals each accessible through an opening in the sheath.

2. As a new article of manufacture, an electrical heating element of the strip type comprising a resistor, an elongated, narrow

sheet metal sheath made up of a plurality of parts enveloping said resistor and spaced therefrom, and an artificially compacted mass of granular refractory electrical insulating material filling the space between the resistor and sheath, the resistor being provided with terminals each accessible through an opening in the sheath.

3. As a new article of manufacture, an electrical heating element of the strip type comprising a resistor, an elongated, narrow sheet metal sheath made up of a plurality of parts enveloping said resistor and spaced therefrom, and a mass of granular refractory electrical insulating material filling the space between the resistor and the sheath, the entire assembly being in a highly compacted state, the resistor being provided with terminals each accessible through an opening in the sheath.

4. As a new article of manufacture, an electrical heating element of the strip type comprising a resistor arranged in flat formation, an elongated, narrow sheet metal sheath made up of a plurality of parts enveloping said resistor and spaced therefrom, and an artificially compacted mass of granular refractory electrical insulating material filling the space between the resistor and sheath, the resistor being provided with terminals each accessible through an opening in the sheath.

5. As a new article of manufacture, an electrical heating element of the strip type, as distinguished from electrical stoves, hot plates and tubular heaters, the same comprising a resistor, an elongated, narrow, relatively thin, seamed sheet metal sheath enveloping said resistor and spaced therefrom, and a mass of granular refractory electrical insulating material of high heat conducting quality filling the space between the resistor and sheath, the resistor being provided with terminals each accessible through an opening in the sheath.

6. As a new article of manufacture, an electrical heating element of the strip type comprising a resistor, an elongated, narrow seamed sheet metal sheath enveloping said resistor and spaced therefrom, and an artificially compacted mass of granular refractory electrical insulating material filling the space between the resistor and sheath, the resistor being provided with terminals each accessible through an opening in the sheath.

7. As a new article of manufacture, an electrical heating element of the strip type, as distinguished from electrical stoves, hot plates and tubular heaters, the same comprising a resistor arranged in flat formation, an elongated, narrow, relatively thin sheet metal sheath enveloping said resistor and spaced therefrom and being oblong in cross section, and a mass of granular refractory electrical insulating material of

high heat conducting quality filling the space between the resistor and the sheath, the resistor being provided with terminals each accessible through an opening in the sheath.

8. As a new article of manufacture, an electrical heating element of the strip type, as distinguished from electrical stoves, hot plates and tubular heaters, the same comprising a resistor, an elongated, narrow, relatively thin sheet metal sheath enveloping said resistor and spaced therefrom, and a mass of granular refractory electrical insulating material of high heat conducting quality filling the space between the resistor and the sheath, the sheath consisting of two main parts closely embracing and enveloping said mass of insulating material, and the resistor being provided with terminals each accessible through an opening in the sheath.

9. As a new article of manufacture, an electrical heating element of the strip type comprising a resistor, an elongated, narrow sheet metal sheath enveloping said resistor and spaced therefrom, and a mass of granular refractory electrical insulating material filling the space between the resistor and the sheath, the sheath being closed at its ends by the pressed together opposed walls of the casing, and the resistor being provided with terminals each accessible through an opening in the sheath.

10. As a new article of manufacture, an electrical heating element of the strip type comprising a resistor, an elongated, narrow sheet metal sheath enveloping said resistor and spaced therefrom, and a mass of granular refractory electrical insulating material filling the space between the resistor and the sheath, the resistor being provided with terminals each accessible through an opening in the sheath, the element having a relatively thin cross section to permit bending of said element to various shapes.

11. As a new article of manufacture, an electrical heating element of the strip type, as distinguished from electrical stoves, hot plates and tubular heaters, the same comprising a resistor, an elongated, narrow, relatively thin sheet metal sheath enveloping said resistor and spaced therefrom, and a mass of granular refractory electrical insulating material of high heat conducting quality filling the space between the resistor and the sheath, the resistor being provided with terminals each accessible through an opening in the sheath, the element having a relatively thin cross section and formed to a desired shape.

12. As a new article of manufacture, an electrical heating element of the strip type comprising a resistor, an elongated, narrow seamed sheet metal sheath enveloping said resistor and spaced therefrom, and an arti-

cially compacted mass of granular refractory electrical insulating material filling the space between the resistor and sheath, the resistor having terminals each accessible through an opening in the wall of the sheath intermediate its ends.

13. As a new article of manufacture, an electrical heating element of the strip type comprising a resistor, an elongated, narrow, formed sheet metal sheath enveloping said

resistor and spaced therefrom, and an artificially compacted mass of granular refractory electrical insulating material filling the space between the resistor and sheath, the resistor having terminals each accessible through an opening in the wall of the sheath.

In testimony whereof, I hereunto affix my signature.

EDWIN L. WIEGAND.
